UNITED STATES PATENT OFFICE.

JAMES W. KEENAN, OF DETROIT, MICHIGAN.

MOLD FOR CONCRETE BASEMENT-WALLS.

1,142,887.

Specification of Letters Patent. Patented June 15, 1915.

Application filed July 11, 1913. Serial No. 778,433.

To all whom it may concern:

Be it known that I, JAMES W. KEENAN, a citizen of the United States of America, residing at Detroit, in the county of Wayne 5 and State of Michigan, have invented certain new and useful Improvements in Molds for Concrete Basement-Walls, of which the following is a specification, reference being had therein to the accompanying drawings.

10 This invention relates to a knock-down mold for concrete basement walls and its object is to provide a mold formed of sections which are interchangeable and are adapted to be set in a vertical position and reach from 15 the footing to the top of a wall so that the entire wall may be made without resetting or changing the mold sections.

A further object of the invention is to provide a construction which is such that 20 the mold may be readily set up to provide for a basement of any desired dimensions and which is so constructed that the window frames and sills may be set in place and molded into the wall during its formation.

25 A further object of the invention is to provide convenient means for alining the mold sections to facilitate the placing of the same and further to provide certain other new and useful features in the construction 30 and arrangement of parts.

To these ends the invention consists in the matters hereinafter set forth and more particularly pointed out in the appended claims reference being had to the accompanying 35 drawings in which—

Figure 1 is a perspective view of a portion of a mold embodying the invention; Fig. 2 is a perspective view of one of the mold sections detached: Fig. 3 is a sectional view of a 40 mold section for use in forming a corner of the wall; Fig. 4 is an enlarged sectional detail of a portion of a mold set up; Fig. 5 is a perspective detail showing a locking device for the sections; Fig. 6 is a transverse vertical section through the mold showing the 45 same in operative position and a filler plate in place therein; Fig. 7 is a perspective view of a filler plate detached; and Fig. 8 is a perspective view of an alining bar.

50 In the construction of concrete walls it has been the common practice to build up a mold of a plurality of horizontally disposed members or to build the wall of sections beginning at the bottom of the wall and lifting 55 the mold upwardly one section at a time as

the filling in progresses and the portion which has been filled in becomes set so that the next section above may be formed thereon.

Applicant proposes to build his mold walls of a plurality of narrow sections set 60 on end and of a length equal to the height of the wall so that the entire wall may be built by filling in the mold without the necessity for resetting or shifting the mold walls and walls of any desired dimensions 65 may be readily made by using a greater or lesser number of sections. Each of these sections 1 comprises a rectangular strip of sheet metal 2 bordered by side angle bars 3 and end angles 4, which are secured to one 70 face of the sheet metal strip at its edges to give strength and rigidity to the strip. These angle bars also serve to hold the sections in position in the mold by being provided with openings near their ends, the side 75 angle bars 3 being each provided with holes 5 equidistant from its ends and the end angle bars 4 being provided with holes 6 which are equidistant from their ends so that the holes in one section will register with those 80 of the next section regardless of which end of the section is placed at the top of the wall or of whether the section is placed within the inner or the outer mold wall.

In setting up the mold footing strips 7 85 are first placed in position in the bottom of the excavation, said strips being spaced apart according to the thickness of the wall to be constructed, and these strips are provided with upwardly extending spaced pins 9 90 adapted to engage the holes 6 in the angle bars on the several sections to hold said sections in place at their lower ends. The several sections to form the inner and the outer walls of the mold are then set up side by 95 side with the pins 9 engaging the openings in their lower ends and the sections are then locked together by means of keys 10 each having a longitudinal slot 11 to receive a wedge 12. The keys are inserted in the holes 100 5 and the wedges then driven into the slots in the keys to draw the contacting flanges of the side angle bars of adjacent sections into close contact and lock them together to form a continuous solid mold wall. The 105 lower ends of the several mold sections are alined and held in perfect alinement by the pins on the footing strips 7 and to aline the upper ends of the several sections and hold them in alinement, flat bars 13 are placed 110

upon the upper edges of the two mold walls formed by the upper ends of the several sections and these alining strips or bars are provided with holes 14 adapted to register 5 with the holes 6 in the end angle bars of the several sections. To hold the inner mold wall spaced at the proper distance from the outer mold wall at its upper edge, spacing bars 15 are provided having a series of holes 10 16 at each end and slotted pins 17 or keys similar to the keys 10 are inserted in the holes in the spacing bars and through the openings in the alining strips and the holes 15 in the upper ends of the several mold sections. These pins are held in place by means of wedges 18 similar to the wedges 12 and thus the two mold walls are firmly held in spaced relation by the spacing bars and the several sections of each wall are held in perfect 20 alignment by the alining strips. To hold the mold in vertical position before the concrete is filled in, brace rods 19 are provided, said rods engaging openings 20 in the side angle bars 3 of each mold section, said 25 openings being positioned equidistant from each end of the sections so that they will register with the openings of the adjacent sections regardless of which end is up when they are placed in the mold.

30 Whenever it is found desirable to place a window frame in the concrete wall, an opening for such a frame may be provided by placing a suitable number of short mold sections 20 in the outer mold wall at the point 35 where it is desired to have the window and after the mold has been filled up even with the upper ends of these short sections, the usual stone window sill 21 is laid in place and the window frame 22 then set in place 40 upon the sill and against the inner mold wall which is formed of full length sections. To form a rounded corner on the concrete wall at each side of the window frame between its outer edge and the outer surface 45 of the wall, a sheet metal forming strip 23 is secured at one edge to the outer edge of the window frame by screws or other suitable means passing through its flanged edge and the opposite edge of the forming strip 50 is secured to the adjacent mold section by providing said strip with an angle bar 24 similar to the angles secured to the mold sections and this angle bar is provided with an opening to register with the opening 5 55 in said adjacent mold section so that the forming strip may be secured in place by means of one of the keys 10. These forming strips are curved or bent in transverse section to form a rounded corner on the 60 concrete wall and may be of any form desired. Window frames and sills may thus be built into the concrete wall at any desired point and are firmly held in place by the concrete of the wall in which the frame 65 and sill are embedded.

If found desirable, an alining bar 30 may be employed to hold the short sections in place at their upper ends, said bar being formed with laterally extending ears 31 formed by severing portions of one flange of 70 the angle bar and turning these portions at right angles to the flange to project inward alongside the flanges of the bar 3 of the sections, said ears being formed with openings 75 to register with like openings in said bars 3 so that the sections may be secured together and the alining bar to the sections, by keys like the keys 10.

In constructing brick veneer buildings it may be desirable to continue the brick veneering down upon the outside of the basement wall to below the ground line, and it is therefore necessary to provide a seat or ledge upon the concrete wall for this veneering. To provide such a seat, the upper portion of the concrete wall is reduced in width by means of a series of filler plates 25 arranged side by side, each of a width equal to the width of the mold sections 1 and each formed from a single piece of sheet 90 metal which is bent at its lower end to form an outwardly extending flange 26 and is similarly bent at its upper end to form a flange 27. The body of the plate may be strengthened to prevent its being bent by the 95 pressure of the concrete against it, by means of an angle strip 28 secured upon its outer face between the end flanges. After the mold walls have been set in place, the filler plates are placed within the mold with their flanges 26 against the inner face of the outer mold wall and their upper flanges 27 engaged over the upper edge of the wall. The flanges 27 are provided with openings 29 spaced apart to correspond with the openings 6 in the ends of the mold sections and to hold the filler plates firmly in place, the pins 17 are inserted through the spacer bars, the openings in the liner strips and through the openings in these filler plates and the 100 corresponding openings in the mold sections. The filler plate is spaced from the outer mold wall by its flanges just far enough to give the desired off-set in the concrete wall and 105 form a seat or shoulder thereon of a width 110 to accommodate the brick veneering.

By forming the mold walls of narrow sections which are of a length equal to the height of the concrete wall to be formed, the mold may be quickly and accurately set up and the same sections used to build up molds for concrete basements of various dimensions and as these mold sections are alike upon both sides and ends they may be placed in either the inner or outer wall of 115 the mold with either end up, thus obviating the necessity for using care in placing the sections and facilitating the erection of the mold. By the use of short mold sections 120 and forming strips, the window frames and 125 sills may be easily and quickly set in place and the sections removed when the concrete 130 is set.

sills may be set in position and the concrete wall formed around them thus securely and accurately holding them in place.

Having thus fully described my invention
5 what I claim is:—

1. In a mold for concrete basement walls, the combination of parallel mold walls each comprising a series of rectangular mold sections, placed edge to edge in a vertical 10 position and having the meeting edges thereof connected, one of said walls having a plurality of short sections, means for detachably securing the several short sections to the mold sections, means for holding the 15 walls spaced apart at their upper end, a footing having means for holding the walls spaced apart at their lower ends, a window frame opposite the short sections, curved strips connecting said frame and the adjacent 20 section at each side of the short sections, and filler plates suspended from the upper edge of the outer mold wall and adapted to form a continuous ledge throughout the length of the molded wall.

25 2. In a mold for concrete basement walls, the combination of parallel mold walls each comprising a series of rectangular mold sections placed edge to edge in a vertical position, and having the meeting edges thereof connected, one of said walls having a plurality of short sections, means for detachably securing the several short sections to the mold sections, means for holding the 30 walls spaced apart at their upper ends, a footing having means for holding the walls spaced apart at their lower ends, a window frame opposite the short sections, and curved strips connecting said frame and the adjacent sections at each side of the short 35 sections.

40 3. In a mold for concrete basement walls the combination of parallel mold walls each comprising a series of rectangular sections set upon end with their sides in contact, means for detachably securing the adjacent edges of the sections together, means for spacing the upper ends of the walls apart, a footing, means on the footing for engaging and spacing the lower ends of the walls 45 apart, a filler plate opposite the upper end of each section forming one of the mold walls and spaced from the inner face of said wall to form a continuous offset throughout the length of the concrete wall for an 50 exterior finishing structure for the wall, means for detachably securing the filler plates in place.

4. In a mold for concrete basement walls, the combination of spaced parallel mold walls each comprising a series of rectangular sections set on end, means for detachably securing the edges of the sections together, means for spacing the upper ends of the walls apart, means for holding the lower ends of the walls in spaced relation, 55 a series of filler plates opposite the upper ends of the several sections forming one mold wall and adapted to form a continuous offset throughout the length of a molded wall, each plate being bent at its lower end 60 to form a flange to engage the inner side of the adjacent mold wall and space said plate therefrom, and means for detachably securing the upper ends of the plates to the sections. 65

70 5. In a mold for concrete walls, a plurality of articulated panel sections, and a series of filler plates having the upper edges thereof flanged and suspended from the upper edges of said sections and against the inner walls thereof to form a continuous ledge throughout the length of a molded wall. 75

80 6. In a mold for concrete walls, a series of articulated mold sections arranged in parallelism, means including pins for spacing the upper and lower ends of one series of sections relatively to the other, and a series of filler plates suspended between the parallel series of mold sections against the inner walls thereof and held in place by the first mentioned means at the upper ends of said sections and adapted to form a continuous ledge throughout the length of a molded wall. 85

90 7. In a mold for concrete walls, series of parallel articulated mold sections, a footing for spacing the lower ends of one series of mold sections relatively to the other, spacing bars spacing the upper ends of one series of mold sections relatively to the other series, and a series of filler plates suspended between the series of parallel mold sections and held in place by said spacing bars and adapted to form a continuous ledge 95 throughout the length of a molded wall for an exterior finishing structure for the wall. 100

105 In testimony whereof I affix my signature in presence of two witnesses.
